SUCTION STRIPPING AND STACKING APPARATUS

Harold J. Goss, Nashua, N. H., assignor to The International Paper Box Machine Company, Nashua, N. H., a corporation of New Hampshire

Application March 31, 1955, Serial No. 498,261

12 Claims. (Cl. 93—51)

This invention relates to machines for making folded boxes of paper or the like and especially to box folding machines of the reciprocating form type.

In such machines the box form moves from a blank receiving position to a box set-up position, near the exit end of a forming channel, and means must be provided to strip the completed box from the form and to discharge the boxes in an orderly manner.

In my prior U. S. Patent No. 1,538,851, issued May 19, 1925 and entitled, "Assembling Mechanism for Box Making Machines" a machine of the above mentioned type is shown, the blanks being moved vertically upward in a channel and delivered to the exit end as a set-up box with the bottom foremost. An upwardly extending box receiving magazine or channel is provided, spaced from, but in axial extension of the forming channel. Mechanism is provided for stripping each successive box from the form moving it into the entrance end of the magazine and stacking the box therein with each alternate box at an opposite tilt to accomplish partial nesting. With boxes having non tapered sides, such partial nesting reduces the space occupied by the boxes to a considerable degree. A preferred embodiment of this invention is illustrated herein as applied to a machine such as disclosed in said prior patent.

The object of the invention is to provide improved means for stripping each box from a box form, feeding it into the entrance of a box magazine or channel and forming a stack of indefinite length therein.

Another object of the invention is to provide vertical stacking apparatus having the additional function of stripping boxes and feeding boxes to the stack.

A further object of the invention is to provide more efficient apparatus for transferring assembled set-up boxes from a box form into the bottom of a vertical stack without danger of fracturing, tearing or otherwise damaging the boxes.

Still another object of the invention is to provide a suction gripper capable of pulling a box into a stack while pushing the preceding box further into the stack and moving the rest of the stack further along the magazine or channel.

Other objects of the invention will be apparent from the following description of the invention, from the claims and from the drawings. The mechanism for forming the boxes and for stacking the boxes at alternate opposite angles is not illustrated in detail in the drawings since it is well known and described in said patents. Such mechanism is shown only in sufficient detail to show the improvements of the present invention.

In the drawings

Fig. 1 is a fragmentary front elevation of the lower portion of a plunger type box forming machine having vertical box stacking mechanism with my invention applied thereto.

Fig. 2 is a fragmentary side elevation of the device shown in Fig. 1.

2

Fig. 3 is a diagrammatic front view illustrating the path of the suction heads of the invention.

Fig. 4 is an enlarged fragmentary perspective view of a pair of adjacent suction heads and the mounting therefor illustrating in dotted lines various positions of angular adjustment, and

Fig. 5 is a view in section on line 5—5 of Fig. 4 showing the rigid suction connections of each head.

As shown, 20 is a box form type machine for making folded paper boxes, the machine 20 having a pair of upstanding side frame pieces 21 and 22, suitable cross support rods such as at 23 and a number of cross shafts to be hereinafter mentioned. The box forming channel 24 and the box form or plunger 25 may be of any well known type. Box form 25 is arranged to support the bottom panel of a flat blank while forcing the blank upwardly through the channel thereby causing the side walls of the blank to fold downwardly into the shape of a set-up box. Suitable interlocking corner tabs, glued stays, glued tabs or the like are used to complete the box on the form all in a well known manner and not requiring illustration. The box form 25 is reciprocated axially of the channel 24 by the plunger rod 26, rod 26 being vertically slideable in fixed guides 27 and 28 and actuated by a crank arm 29. The blank receiving position of box form 25 is indicated at 32 and the box set-up position is indicated at 33, the latter being proximate the exit end 34 of box forming channel 24.

A box receiving channel or magazine 35 is provided preferably coaxial with, and in projection of, forming channel 24 but having its entrance end 36 spaced from the exit end 34 thereof. I use the term exit end of the box forming channel to mean the forward limit of the stroke of the box form reciprocating therein because even if the box forming channel extends beyond this forward limit, it accomplishes no further box forming function. I use the term entrance end of the box receiving channel to mean the rearward or bottom limit of a stack of boxes therein, because it is only after a box has advanced past said limit that it forms a part of a stack and is actually in a magazine. It should be noted therefore, that while the exit end of the box forming channel is spaced from the entrance end of the box receiving channel, to provide axially extending space for stripping a box from the box form, portions of the walls of the two channels could be integral and in extension of each other if desired.

The box receiving channel 35 is formed by spaced apart vertical guides such as 37 and 38 supported on the machine 20 by brackets such as 39 and cross rods such as 40. Guides 37 and 38 may extend vertically upward as far as desired, but with tapered set-up boxes, or non-tapered partial nested boxes, the stack is self supporting and may extend well above the top of the guides. As best shown in Fig. 3, oppositely disposed spring pressed pivoted catches such as 43 and 44 mark the entrance end of box receiving channel 35 and are designed to pass an upwardly moving set-up box but prevent its passage downwardly in the channel. Similar catches 45 and 46 are provided further along the channel for a similar purpose and these catches support the entire stack from falling downwardly in a vertical channel such as shown. Suitable jogging mechanism indicated by the numeral 47, and described in my above mentioned patent, may be provided to partially nest non-tapered boxes in the manner illustrated.

As thus far described, the mechanism for folding, jogging and retaining boxes in the stack, is in accordance with my prior patent. The improved apparatus of this invention for stripping each successive box from the box form, moving the box into the entrance end of the magazine and then moving the box and the box stack along the magazine will now be described.

Suction gripper means 50 is provided, preferably in the form of the elongated straight body 51, of rigid material such as metal, having a suction cup 52 mounted on one side or face 53 thereof near an end 54 of the body. The opposite end 55 of each body 51 is pivotably mounted by a pivot bolt 56 to an opposite arm 57 or 58 of a cross head 59 whereby the body 51 may be turned through various angles in a plane parallel to the plane of the suction face 60 of cup 52. Cup 52 is of resilient material whereby it will yield as it adheres to a flat surface such as the bottom panel 63 of an assembled set-up box such as 64.

Preferably the elongated body 51 includes a first suction opening 65 in face 53 at end 54 to which cup 52 is connected and a second suction opening 66 in face 53, at end 55, connected to the suction means of the invention. A suction conduit 67 in the form of an axial bore extends axially within and along body 51 for connecting the suction openings 65 and 66. It should be noted that the axis of suction opening 67 and of pivot bolt 56 is parallel to the axis of suction opening 65 and yieldable suction cup 52. A single large area suction cup 52 forming part of a single suction gripper means 50 might perform adequately in the invention but preferably two oppositely disposed pair of such suction gripper means 50 are provided to secure a firm grip near each of the four corners of each successive box 64 and to permit angular pivoting on pivot bolts 56 to accommodate various sizes of boxes.

The pusher means 70 of the invention is preferably integral with suction gripper means 50 and movable therewith. Pusher means 70 comprises the flat, smooth, antifriction face 71 of the elongated body 51 and is arranged to engage and push on the outer edges such as 72 of the upstanding walls such as 73 of each set-up box 64 in its path. Each suction gripper means 50 is thus conveniently in the form of a single head having a suction opening, face or cup on one side and a smooth, flat box pusher face on the opposite side, to permit the head to perform a double function in its path of movement.

Means for moving the suction gripper means 50 and box pusher means 70 includes the crossheads 59 and 75 each cross head being fixed to a rigid tube 76 or 77 supported by one of a pair of brackets such as 78. Each bracket such as 78 includes a split sleeve 79 tightenable on a tube such as 77 at one end and includes a pair of sleeves such as 80 at its other end. The two sleeves such as 80 of each bracket are slideable horizontally crosswise of machine 20 on a pair of tracks such as 81 and the tracks 81 are supported at each opposite end by one of a pair of oppositely disposed rods 82 or 83. Each rod such as 82 is vertically slideable, parallel to the path of box form rod 26 in roller guides such as 84.

A connecting rod 86 pivotably connects rod 83 to a crank arm 87 rotated on a cross shaft 88. Shaft 88 is journaled in frame pieces such as 89 and carries a sprocket 90 around which a chain 92 is trained. Chain 92 is trained around a similar sprocket 95 and carried by a drive shaft 93 rotated by drive means 94 of any well known type such as an electric motor. The above described reciprocating mechanism is duplicated on each side of the machine as shown in Fig. 1 and it will be apparent that each rotation of the crank arms such as 87 causes the suction means 50, the cross heads 59 and 75, the tubes 76 and 77, the brackets such as 78 and the tracks such as 81 to be raised on a forward stroke and lowered on a rearward stroke. The sleeves 80 of the brackets are slideable on tracks 81 and each bracket includes lugs such as 96 guided on one of a pair of depending arms such as 97 or 98.

Arm 97 depends from a gear rack rod 99 and arm 98 depends from a gear rack rod 100, the gear rack rods being slideable crosswise of machine 20 in side frames 21 and 22 and movable jointly in opposite directions by a common gear 101. Thus sidewise movement of one arm

such as 97 results in movement in the opposite direction of the other arm whereby the arms are jointly movable toward and away from each other. One gear rack rod such as 100 is pivotally connected at 102 to one end of a lever 103, the lever 103 being pivoted at 104 to a cross rod 105. The other end of lever 103 carries a cam follower 106 engaged in the path 107 of a path cam 108. Cam 108 is mounted on a shaft 109 journaled at each opposite end in a bearing such as 111 in frames 21 and 22 and carries a gear 112 meshed with a gear 113. Gear 113 is mounted on a stub shaft 114 carrying a sprocket 115 which in turn is rotated by a chain 116 powered by a sprocket 117 on drive shaft 93. Thus each rotation of path cam 108 causes the gear rack rods 99 and 100, the arms 97 and 98, the brackets and cross heads and the suction means 50 to move outwardly away from each other in the same plane and then back toward each other in the same plane. The resulting path of the suction means 50 caused by the combined actuation of crank arms 87 and path cam 108 is synchronized in timed relation with the reciprocation of box form 25 by the common drive shaft 93 and is shown in its preferred form in Fig. 3.

The suction means 120 of the invention includes the cross heads 59 and 75 and the rigid tubes 76 and 77. The cross heads each include a suction conduit 121 connecting with the suction means 50 at each opposite end thereof and connecting within the central post 122 with the bore of the tube fixed to the post. The upper end of each tube 76 or 77, at 123 is connected to a flexible tube 124 or 125 leading to a suction tube 126 mounted on machine 20. Tube 126 is connected by a flexible tube 127 to a suction control valve 128 mounted on a stub shaft 129 to a side frame 22. Valve 128 includes a rotary plug 130 revolved by a sprocket 130, the sprocket 130 being connected by a chain 131 to a sprocket 132 on shaft 133. Shaft 133 in turn is rotated by drive means 134 but synchronized in timed relation to the other parts of the machine in a well-known manner. Valve 128 is connected by a tube 135 to a source of suction not shown such as a suction tank and pump of any well known type. The valve 128 is arranged to apply suction in suction means 50 at the commencement of a forward or upward stroke of the device, maintain such suction during the stroke and release the suction near the end of the stroke.

In operation, the machine 20 continually produces set-up boxes by means of the box form 25 reciprocating in the forming channel 24 from blank receiving position 32 to box set-up position 33. The crank arm 29 which actuates the forming mechanism is driven by the drive shaft 93, which shaft is directly or indirectly the drive shaft of all of the mechanism of the machine. Each individual and successive box such as 64 is presented bottom foremost at the exit end 34 of forming channel 24 and each corner portion of the bottom panel 63 thereof is flatwise engaged by the suction faces 60 of the suction cups 52. Valve 128 applies suction in the cups to cause them to adhere firmly to the bottom panel 63 preparatory to stripping the box from box form 25. The above described means for moving the suction means 50 then moves the suction grippers forwardly and rectilinearly from the exit end 34 to the entrance end 36 of box receiving channel 35. The box enters the channel 35 bottom foremost and passes beyond the spring catches 43 and 44 which mark the entrance thereof and valve 128 then releases the suction in cups 52. As shown in Fig. 3 the cups 52 then move outwardly away from each other in the same plane in opposite loops and return to their starting point in a path which extends around the box 64 and extends at least partially outside the space between exit end 34 and entrance end 36. Upon again arriving at the exit end 34, in timed relation to the movements of box form 25, suction is again applied by valve 128 and the next succeeding box 140 is stripped

from form 25 and moved to receiving channel 35. The flat face 71 of pusher means 70, on this and succeeding cycles of operation, engages the outer edges 72 of walls 73 of the previously fed box such as 64 and pushes that box further into channel 35 to be caught by a second set of spring catches such as 45 and 46. Box 64 thus becomes the bottom or endmost box of the stack and pushes the entire stack further along the receiving channel 35. As shown in the drawing, the jogging mechanism 47 described in my prior patent oppositely tilts each alternate box to accomplish partial nesting as shown. The guides 37 and 38 forming channel 35 may overlap the path of the suction means 50 because the latter moves outwardly in a space between the guides.

I claim:

1. In a machine for making boxes said machine having a box forming channel with an exit end, box forming means reciprocable in said forming channel and a box receiving channel with an entrance end, said channels being coaxial and facing each other with said ends spaced apart, suction gripper means facing toward said box forming channel and adapted to secure a grip on a box positioned bottom foremost at the exit end thereof, means for moving said suction gripper means up to said entrance end along a predetermined path located in the space between said ends and moving said suction gripper means back to said exit end along a predetermined path at least partly located beyond the space between said ends, said moving means being cooperable with said box forming means to remove each successive box therefrom and advance the box bottom foremost into the entrance end of the box receiving channel; suction means operably connected to said gripper means, including mechanism for releasing suction in said suction gripper means to disengage a box therefrom at the entrance end of said box receiving channel and box pusher means on, and movable with, said suction gripper means, said pusher means facing toward said box receiving channel and being adapted to push further into said channel, each successive box released at the entrance end thereof on the previous path circuit of said suction gripper means.

2. A combination as specified in claim 1 wherein said suction gripper means comprises a pair of oppositely disposed suction heads and said moving means includes means for moving said heads in opposite closed paths in a common plane.

3. A combination as specified in claim 1 wherein said suction gripper means and said pusher means are carried on a single head extending perpendicularly to the axis of said channels, said head having a suction gripper facing the box forming channel and a smooth, anti-friction box pusher face facing the box receiving channel.

4. A combination as specified in claim 1 wherein said suction gripper means includes a yieldable suction cup positioned on said moving means to flatwise engage the bottom panel of a box in said box forming channel and said box pusher means is positioned on said suction gripper means to flatwise engage opposite upper edges of the walls of a box in said box receiving channel.

5. In a machine for making boxes said machine having a box forming channel with an exit end, box forming means, reciprocable in said channel for presenting successive boxes, bottom foremost, at said exit end and box stacking means, aligned with, but spaced from, said box forming channel for receiving and stacking successive boxes bottom foremost, a pair of movable heads, each extending perpendicular to the axes of said channels on an opposite side thereof, means for moving each said head, cooperably with said box forming means, in opposite closed unidirectional paths in the same plane, the adjacent portions of said paths extending from said exit end to said box forming channel in the space therebetween and the remote portions of said paths being outside said space, a suction cup on each said head facing

said box forming channel and adapted to engage the bottom of a box at the exit end thereof; a smooth, anti-friction surface on each said head, facing said box stacking means, and adapted to engage the edges of the walls of a box in said stacking means, and suction means, cooperable with said moving means for creating and releasing suction in said suction cup in timed relation to the travel of said heads.

6. In a machine for making boxes, said machine having a box forming channel with an exit end, a box form reciprocable in said channel from a blank receiving station to a box set-up station at said exit end and a box stacking channel having an entrance end spaced from, and aligned with, the exit end of said box forming channel, box pusher means movable on a forward stroke in the path of a box between said exit end and said entrance end and movable on a rearward stroke outside said path back to said exit end; a rearward facing suction gripper movable with said pusher means and arranged to extract each successive box from said box form at said exit end, by adhesion to the box bottom, carry said box along said path into the entrance end of said box receiving channel and release said box in the path of said pusher means on its succeeding forward stroke; means for moving said pusher means in synchronization with the movement of said box form and suction means for controlling the suction in said suction gripper in synchronization with the movement of said box form and pushing means.

7. Apparatus for feeding set-up boxes from a box forming device to a box stacking device, said devices being spaced apart and said boxes being bottom foremost, said apparatus comprising suction gripper means adapted to secure a grip on the bottom panel of a box, means for moving said suction gripper means in a closed, unidirectional path forwardly to said box stacking device in a straight line and rearwardly to said box forming device in an outward loop; suction means for maintaining suction in said gripper means during the forward component of said path to engage a box and for releasing suction in said gripper means, proximate the end of said forward component, to disengage a box and box pusher means movable with, and leading each said suction gripper means on its said path, said pusher means being adapted to engage a rearward facing portion of a box previously released in said path by said suction gripper means and to push said box further into said box stacking device.

8. Apparatus for feeding set-up boxes bottom foremost from a box forming device to a coaxial box stacking device spaced therefrom, said apparatus comprising at least two suction grippers, each adapted to secure a grip on an opposite side of the bottom of a box in said box forming device; means for moving each said gripper in a closed unidirectional path having a forward component extending from said box forming device to said box stacking device in the space therebetween and having a portion of the remaining component of said path lying outside the space therebetween, suction means cooperable with said moving means, for releasing suction in said grippers proximate the end of said forward component to disengage a box and box pusher means, facing forwardly on each gripper during said forward component and movable therewith, said pusher means being adapted to contact each box disengaged on a previous circuit of said path and push said box further along said path.

9. Apparatus as specified in claim 8 wherein each suction gripper is pivotably connected to said moving means for turning in the plane of the bottom of a box whereby box bottoms of various dimensions may be gripped thereby.

10. Apparatus as specified in claim 8 wherein each suction gripper comprises a head of rigid material having a flexible suction cup facing rearwardly therefrom and a smooth anti-friction surface facing forwardly therefrom, to constitute said pusher means.

11. Apparatus as specified in claim 8 wherein said moving means comprises a pair of brackets each reciprocable perpendicular to the axes of said devices in an opposite direction on tracks and each supporting a gripper, tracks reciprocating parallel to said axis and slideably supporting said brackets and means for reciprocating said brackets on said tracks in timed relation to the reciprocations of said carriage to move said grippers in opposite closed paths in the same plane.

12. In combination with a box form folding machine having a spaced box receiving magazine, suction means, including a movable suction head adapted to push each successive box further into said magazine while pulling

the next succeeding box from said machine into said magazine and means for moving said suction head in a closed unidirectional predetermined path rectilinearly between said machine and magazine and in an outward curvilinear loop between said magazine and machine.
